DUAL WINDOW WASHING DEVICE

Frank Grooms Holmes, Philadelphia, Pa.

Application June 19, 1947, Serial No. 755,596

6 Claims. (CL. 15—252)

This invention relates to a dual window washing device adapted to simultaneously moisten or wipe both sides of the window at one stroke of the device over the window.

It is an object of the present invention to provide a window washing device which can be quickly connected to a window and which will have devices for cleaning and wiping extended on both surfaces of the window once the device has been connected to the same and wherein with one stroke both window surfaces can be moistened or wiped and wherein a minimum number of operations for effecting the connection of the window device are had.

It is another object of the present invention to provide in a window washing device two elements, one disposed on one side of the window and one on the other and wherein these elements have a multiple number of engaging portions, any one of which may be adjusted for engagement with the window surface and wherein a common means is utilized for adjusting the elements together when arranged on the opposite sides of the window, this means being able to lock the elements in spring-pressed engagement with the window.

Other objects of the present invention are to provide a window washing device which is of simple construction, easy to handle, quickly assembled upon the window, inexpensive to manufacture, and efficient in operation.

According to the invention, there are provided holes extending through the sides of the window in which are respectively disposed hollow members with diametrically opposed slots cooperating with slots of the window frame through which the ends of the window washing device can be extended when the hollow members have been rotated so that their slots have been aligned with the slots of the window frame. When the hollow members have been rotated to a closed position, they will close the openings in the window frame and prevent the insertion of the ends of the window washing device therethrough.

The window washing device has two ends which can be extended through the window frame openings and carry two washing elements, one of which is fixed to the frame and urged against the window by compression springs while the other of which is removably connected to the ends of the frame to act upon the opposite side of the window. The latter washing element is not disposed on the frame until the end of the frame has been extended through the openings from one side to the other. The compression springs keep both window washing elements in

tight engagement with the window surface. Each washing element has four arms on the same and on these arms are moistening and wiping elements.

Within each end of the supporting frame is a rack which cooperates with gear pinions on the washing elements to effect the rotation of the same whereby to present either moistening or wiping elements to the window surface. These racks can be retained in any of their adjusted positions. The racks are retained in their extended positions except when latched in intermediate positions. In all positions they are pressed by a compression spring carried upon a rotatable spindle on the end of the rack.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a window frame constructed according to the present invention, with the washing device of the present invention connected thereto.

Fig. 2 is an elevational view of the hollow member removed from the side of the window frame.

Fig. 3 is an enlarged transverse cross sectional view taken on line 3—3 of Fig. 1, looking in the direction of the arrows thereof.

Fig. 4 is a transverse cross sectional view taken through the window washing device on the line 4—4 of Fig. 1, looking in the direction of the arrows thereof.

Fig. 5 is an enlarged cross sectional view taken through the window washing device on line 5—5 of Fig. 1, looking in the direction of the arrows thereof.

Fig. 6 is an enlarged fragmentary view of one of the washing elements.

Fig. 7 is an enlarged end elevational view, with portions broken away, of one end of the window washing device.

Fig. 8 is an enlarged cross sectional view taken on line 8—8 of Fig. 7, looking in the direction of the arrows thereof.

Fig. 9 is a top plan view of a window washing device and a section taken on line 9—9 of Fig. 1, looking in the direction of the arrows thereof.

Referring now to the figures, 21 represents a window frame having side portions 22 and a glass 23 therein. The side portions 22 have elongated slots 24 extending vertically therethrough in

which there are mounted hollow members 25 for rotatable adjustment therein. At the bottom end of each hollow member 25 there is a handle 26 which extends outwardly through an opening 27 at the bottom of the window frame 21 by which the hollow member can be rotated.

The hollow members 25 also have elongated vertically extended slots 28 adapted to be aligned with the exterior portions of the slots 24 in the frame so that the window frame may receive side arms 29 of a window washing device 30. When the window washing device 30 is to be mounted upon the window, the hollow members 25 are turned so that their slots 28 are aligned with the slots 24 of the window frame, see Fig. 3, so that the ends of the side arms 29 can be passed through those aligned slots.

The window washing device 30 has a handle portion 31 which extends from one side arm 29 to the other. The side arms 29 are of channel section and are notched near their ends as indicated at 32 to removably contain a washing element 33. With the washing element 33 removed, the ends can be inserted through the window frame. Thereafter, the washing element 33 is fitted into the notches 32. The washing element has four arms 34 and on alternate arms are moistening and wiping members 35 and 36.

Carried at all times on the washing device so there is a second washing element 37 of the same construction as the washing element 33. The ends of this washing element are backed up by a compression spring device 38, one of said devices being disposed in each arm 29, which tends to hold the washing element 37 against the window glass 23 and simultaneously, it will cause the washing element 33 to be brought in, in yielding engagement with the window glass at its side of the window.

In order to adjust the window elements to present different moistening and wiping members to the glass surface, there are provided adjustable racks 41 in each of the side arms 29, cooperating respectively with pinion gears 42 and 43 on the washing elements 33 and 37 to simultaneously adjust them as the racks 41 are slid relative to the side arms 29. On the end of each rack 41 adjacent the handle 31 of the frame, there is turnably connected for rotatable adjustment a rod 44 having an operating arm 45 thereon adapted to be inserted in any one of a series of notches 46 formed through each of the side arms 29. Each rod 44 carries a compression spring 47 which will tend to keep the respective rack 41 in a locked condition by urging the arm 45 thereof against the side of the particular notch with which the arm 45 is engaged. There are four notches 46, one for each arm of the washing elements 33 and 37.

The notches 46 are formed along the top edges of slots 48 formed in the outer walls of the side arms 29. Thus, the operating arms 45 may be manually disengaged from the notches 46, with which they are engaged, and moved into the slots 48 freeing the rods 44 and the racks 41 to be moved longitudinally to turn the washing elements 33 and 37. This movement aligns the arms 45 with another set of notches 46 with which they can be engaged for locking the racks 41 in their new positions. The rotative connection of the rods 44 with the ends of the racks 41 permits the arms 45 to be engaged with and disengaged from the notches 46.

It should now be apparent that there has been provided a window washing device which can be

quickly and easily installed upon the window and wherein the washing elements 33 and 37 thereof will be operated on opposite sides of the window at the same time and with a single stroke of the washing device 30 and wherein a rotatable adjustment of the washing elements 33 and 37 can be made by the operating arms 45 on the side arms 29 to present different moistening and wiping members to the surfaces of the glass.

It is to be understood that the wipers used in this device may be telescopic to make the same adjustable to fit various sizes of windows.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In combination with a window having a frame enclosing a window pane and formed along the sides thereof with vertical slots, a device for cleaning the inner and outer surfaces of the pane, comprising a U-shaped frame having hollow side arms extended through the vertical slots and an intermediate handle portion located inside the window pane for moving the U-shaped frame up and down within the lengths of the slots, a washing element having radially extended arms provided at their free ends with wiping members rotatively supported between said side arms on the inner side of the pane for cleaning the inner side of the pane as the U-shaped frame is moved vertically, said side arms being formed with laterally aligned notches spaced from said washing element to be located outside of the window pane when said washing element is engaged against the inner face of the window pane, a second washing element having radially extended arms provided at their free ends with wiping members removably and rotatively supported in said notches and extended between said side arms for cleaning the outer side of the window pane as the U-shaped frame is moved vertically, means within the side arms for turning the washing elements to align a fresh wiping member with the inner and outer surfaces of the window pane, and means for locking said washing elements against rotation with desired wiping members engaging the inner and outer surfaces of the window panes.

2. In combination with a window having a frame enclosing a window pane and formed along the sides thereof with vertical slots, a device for cleaning the inner and outer surfaces of the pane, comprising a U-shaped frame having hollow side arms extended through the vertical slots and an intermediate handle portion located inside the window pane for moving the U-shaped frame up and down within the lengths of the slots, a washing element having radially extended arms provided at their free ends with wiping members rotatively supported between said side arms on the inner side of the pane for cleaning the inner side of the pane as the U-shaped frame is moved vertically, said side arms being formed with laterally aligned notches spaced from said washing element to be located outside of the window pane when said washing element is engaged against the inner face of the window pane, a second washing element having radially extended arms provided at their free ends with wiping members

5

removably and rotatively supported in said notches and extended between said side arms for cleaning the outer side of the window pane as the U-shaped frame is moved vertically, means within the side arms for turning the washing elements to align a fresh wiping member with the inner and outer surfaces of the window pane, and means for locking said washing elements against rotation with desired wiping members engaging the inner and outer surfaces of the window panes, said turning means comprising pinions mounted on the ends of said washing element within the side arms of said U-shaped frame, and racks slidably mounted within said side arms and meshing with said pinions to turn said pinions to in turn rotate said washing elements in one direction or the other as said racks are moved.

3. In combination with a window having a frame enclosing a window pane and formed along the sides thereof with vertical slots, a device for cleaning the inner and outer surfaces of the pane, comprising a U-shaped frame having hollow side arms extended through the vertical slots and an intermediate handle portion located inside the window pane for moving the U-shaped frame up and down within the lengths of slots, a washing element having radially extended arms provided at their free ends with wiping members rotatively supported between said side arms on the inner side of the pane for cleaning the inner side of the pane as the U-shaped frame is moved vertically, said side arms being formed with laterally aligned notches spaced from said washing element to be located outside of the window pane when said washing element is engaged against the inner face of the window pane, a second washing element having radially extended arms provided at their free ends with wiping members removably and rotatively supported in said notches and extended between said side arms for cleaning the outer side of the window pane as the U-shaped frame is moved vertically, means within the side arms for turning the washing elements to align a fresh wiping member with the inner and outer surfaces of the window pane, and means for locking said washing elements against rotation with desired wiping members engaging the inner and outer surfaces of the window panes, said turning means comprising pinions mounted on the ends of said washing element within the side arms of said U-shaped frame, and racks slidably mounted within said side arms and meshing with said pinions to turn said pinions to in turn rotate said washing elements in one direction or the other as said racks are moved, and means for moving said racks.

4. In combination with a window having a frame enclosing a window pane and formed along the sides thereof with vertical slots, a device for cleaning the inner and outer surfaces of the pane, comprising a U-shaped frame having hollow side arms extended through the vertical slots and an intermediate handle portion located inside the window pane for moving the U-shaped frame up and down within the lengths of the slots, a washing element having radially extended arms provided at their free ends with wiping members rotatively supported between said side arms on the inner side of the pane for cleaning the inner side of the pane as the U-shaped frame is moved vertically, said side arms being formed with laterally aligned notches spaced from said washing element to be located outside of the window pane when said washing element is engaged against the inner face of the window pane, a second wash-

6

ing element having radially extended arms provided at their free ends with wiping members removably and rotatively supported in said notches and extended between said side arms for cleaning the outer side of the window pane as the U-shaped frame is moved vertically, and means within the side arms for turning the washing elements to align a fresh wiping member with the inner and outer surfaces of the window pane, 10 said means comprising pinions mounted on the ends of said washing element within the side arms of said U-shaped frame, and racks slidably mounted within said side arms and meshing with said pinions to turn said pinions to in turn rotate said washing elements in one direction or the other as said racks are moved, rods connected at one end with said racks for turning movements relative thereto and extended axially therefrom, slots formed in the outer side walls of said side 20 arms along side said rods, and operating arms extended radially from said rods and through said slots to be moved along the length of said slots for moving said racks, said side walls of said side arms being formed with spaced notches along 25 the top edges of said slots into which said operating arms can be engaged by turning said rods relative to said racks for releasably holding said racks in a desired adjusted position.

5. In combination with a window having a frame enclosing a window pane and formed along the sides thereof with vertical slots, a device for cleaning the inner and outer surfaces of the pane, comprising a U-shaped frame having hollow side arms extended through the vertical slots and an intermediate handle portion located inside the window pane for moving the U-shaped frame up and down within the lengths of the slots, a washing element having radially extended arms provided at their free ends with wiping members 30 rotatively supported between said side arms on the inner side of the pane for cleaning the inner side of the pane as the U-shaped frame is moved vertically, said side arms being formed with laterally aligned notches spaced from said washing element to be located outside of the window pane 35 when said washing element is engaged against the inner face of the window pane, a second washing element having radially extended arms provided at their free ends with wiping members 40 rotatively supported between said side arms on the inner side of the pane for cleaning the inner side of the pane as the U-shaped frame is moved vertically, said side arms being formed with laterally aligned notches spaced from said washing element to be located outside of the window pane 45 when said washing element is engaged against the inner face of the window pane, a second washing element having radially extended arms provided at their free ends with wiping members 50 removably and rotatively supported in said notches and extended between said side arms for cleaning the outer side of the window pane as the U-shaped frame is moved vertically, and means within the side arms for turning the washing elements to align a fresh wiping member with 55 the inner and outer surfaces of the window pane, said means comprising pinions mounted on the ends of said washing element within the side arms of said U-shaped frame and racks slidably mounted within said side arms and meshing with 60 said pinions to turn said pinions to in turn rotate said washing elements in one direction or the other as said racks are moved, rods connected at one end with said racks for turning movement relative thereto and extended axially therefrom, slots formed in the outer side walls of said side arms along side said rods, and operating arms extended radially from said rods and through 65 said slots to be moved along the length of said slots for moving said racks, said side walls of said side arms being formed with spaced notches along the top edges of said slots into which said operating arms can be engaged by turning said rods relative to said racks for releasably holding 70 said racks in a desired adjusted position, and

means retaining said rods in a position in which said operating arms will be in engagement with the material of said side walls defining said notches to frictionally retain said operating arms against disengagement from said notches with which they are engaged.

6. In combination with a window having a frame enclosing a window pane and formed along the sides thereof with vertical slots, a device for cleaning the inner and outer surfaces of the pane, comprising a U-shaped frame having hollow side arms extended through the vertical slots and an intermediate handle portion located inside the window pane for moving the U-shaped frame up and down within the lengths of the slots, a washing element having radially extended arms provided at their free ends with wiping members rotatively supported between said side arms on the inner side of the pane for cleaning the inner side of the pane as the U-shaped frame is moved vertically, said side arms being formed with laterally aligned notches spaced from said washing element to be located outside of the window pane when said washing element is engaged against the inner face of the window pane, a second washing element having radially extended arms provided at their free ends with wiping members removably and rotatively supported in said notches and extended between said side arms for cleaning the outer side of the window pane as the U-shaped frame is moved vertically, and means within the side arms for turning the washing elements to align a fresh wiping member with the inner and outer surfaces of the window pane, said means comprising pinions mounted on the ends of said washing element within the side arms of said U-shaped frame and racks slidably

mounted within said side arms and meshing with said pinions to turn said pinions to in turn rotate said washing elements in one direction or the other as said racks are moved, rods connected at one end with said racks for turning movement relative thereto and extended axially therefrom, slots formed in the outer side walls of said side arms along side said rods, and operating arms extended radially from said rods and through said slots to be moved along the length of said slots for moving said racks, said side walls of said side arms being formed with spaced notches along the top edges of said slots into which said operating arms can be engaged by turning said rods relative to said racks for releasably holding said racks in a desired adjusted position, and means retaining said rods in a position in which said operating arms will be in engagement with the material of said side walls defining said notches to frictionally retain said operating arms against disengagement from said notches with which they are engaged, said retaining means comprising expansion springs operating between said rods and the adjacent end walls of said side arms.
